FIG. 5

FIG. 1

FIG. 2

FIG. 3

FIG. 4

FIG. 7

FIG. 6

FIG. 8

FIG. 1 is a perspective view from the rear of an infant's dressing table embodying the elements of my new design, with the top in its closed position;

FIG. 2 is a front view on a larger scale showing the top of the FIG. 1 table in greater detail;

FIG. 3 is a bottom view thereof;

FIG. 4 is a rear view thereof;

FIG. 5 is a perspective view from the rear thereof;

FIG. 6 is a view similar to FIG. 1 with the top in its open position;

FIG. 7 is a similar view on a larger scale showing the open top in greater detail; and

FIG. 8 is a right side view thereof.

The design is characterized by the shell-like top of the infant's dressing table, as best illustrated in FIGS. 5 and 7.

I claim:

The ornamental design for an infant's dressing table, substantially as shown.
